UNITED STATES PATENT OFFICE.

HERBERT J. A. SKIPP, OF PROVIDENCE, RHODE ISLAND, ASSIGNOR TO J. A. SCHWARZ CO., OF PHILADELPHIA, PENNSYLVANIA, A CORPORATION OF PENNSYLVANIA.

DESIGN FOR A FINGER-RING OR SIMILAR ARTICLE OF JEWELRY.

52,353.

Specification for Design.

Patented Aug. 27, 1918.

Application filed March 11, 1916. Serial No. 83,669. Term of patent 14 years.

To all whom it may concern:

Be it known that I, HERBERT J. A. SKIPP, a citizen of the United States, residing at Providence, in the county of Providence and State of Rhode Island, have invented a new, original, and ornamental Design for a Finger Ring or Similar Article of Jewelry, of which the following is a specification, reference being had to the accompanying drawing, forming a part thereof.

The figure is a plan view of a finger ring or similar article of jewelry showing my new design.

I claim:

The ornamental design for a finger ring or similar article of jewelry as shown.

HERBERT J. A. SKIPP.
